United States Patent Office.

FRANZ HÜTWOHL, OF NEW YORK, N. Y.

Letters Patent No. 75,920, dated March 24, 1868.

IMPROVED FURNITURE-EDGE.

The Schedule referred to in these Letters Patent and making part of the same.

TO ALL WHOM IT MAY CONCERN:

Be it known that I, FRANZ HÜTWOHL, of the city, county, and State of New York, have invented a new and improved Furniture-Edge; and I do hereby declare that the following is a full, clear, and exact description thereof, which will enable others skilled in the art to make and use the same, reference being had to the accompanying drawings forming a part of this specification, in which—

Figure 1 represents a plan or top view of my improved furniture-edge.

Figure 2 is a transverse section of the same.

Similar letters of reference indicate corresponding parts.

This invention relates to a new manner of arranging the edges of upholstered furniture, seats, and backs, and consists in forming, as an independent article of manufacture, a stuffed roll of horse-hair, moss, or other suitable material covered with canvas, which is arranged with its threads diagonally across the roll, so that the latter can be bent into all curvies or corners that may have to be formed on the seat or back of the furniture.

Heretofore such edges were formed by sewing the roll into the canvas, which is stretched over and covers the whole seat or back of the furniture, and not only does the formation of the roll on the furniture occupy much time and labor, but also the stretching of the canvas is made impossible, as one set of its threads is at right angles with the edge of the furniture, while the other set is about parallel with the same.

Those threads that reach across the roll cannot be stretched without being torn, while the others are of no use at all. But when the threads are laid diagonally across the roll, both sets of threads do their work, and the whole fabric can be stretched. In using the threads diagonally across the roll, they would also have to be laid diagonally over the seat or back, if the edge would be formed as part of the whole upholstery. As that is impracticable, it is necessary to form the edges previously, as I propose.

A, in the drawing, represents the roll, which is made of moss, horse-hair, or other suitable material, *a*, covered with canvas, *b*, in the manner shown in fig. 2. The outer edge of the canvas, *b*, is nailed to the frame of the seat or back, while the inner edge is sewed to the canvas covering *b* of the seat or back. The threads of the canvas, *b*, are arranged diagonally across the roll, as in fig. 1.

Having thus described my invention, I claim as new, and desire to secure by Letters Patent—

As a new article of manufacture, a stuffed furniture-edge, A, the covering canvas *b* of which has its threads arranged diagonally across the surface of the roll A, substantially as herein shown and described.

FRANZ HÜTWOHL.
